US0D1053713S

(12) **United States Design Patent** (10) Patent No.: **US D1,053,713 S**
(45) Date of Patent: ** Dec. 10, 2024

(54) **ECOLOGY TAB**

- (71) Applicant: **Stolle Machinery Company, LLC**, Centennial, CO (US)
- (72) Inventors: **Dennis Cornelius Stammen**, Brookville, OH (US); **Robert Joseph Will**, Maria Stein, OH (US); **Christopher Lawrence Macke**, Sidney, OH (US); **Patrick Kevin McCarty**, Dayton, OH (US); **Robert Herbert Brussell**, New Bremen, OH (US); **Greg Scott Williams**, Wapakoneta, OH (US); **Steven Todd Albright**, Covington, OH (US)
- (73) Assignee: **Stolle Machinery Company, LLC**, Centennial, CO (US)
- (**) Term: **15 Years**
- (21) Appl. No.: **29/869,101**
- (22) Filed: **Dec. 21, 2022**

Related U.S. Application Data

- (63) Continuation of application No. 29/839,989, filed on May 25, 2022, now Pat. No. Des. 977,970, which is a continuation of application No. 29/734,199, filed on May 11, 2020, now Pat. No. Des. 959,980.

(57) **CLAIM**

The ornamental design for an ecology tab as shown and described.

DESCRIPTION

FIG. 1 is a top perspective view of the ecology tab; FIG. 2 is another top perspective view of the ecology tab; FIG. 3 is a bottom perspective view of the ecology tab; FIG. 4 is another bottom perspective view of the ecology tab; FIG. 5 is a top plan view of the ecology tab; FIG. 6 is a bottom plan view of the ecology tab; FIG. 7 is a side elevation view of the ecology tab; FIG. 8 is a section view taken in the direction of line 8-8 shown in FIG. 5; FIG. 9 is a front end elevation view of the ecology tab; and, FIG. 10 is a back end elevation view of the ecology tab. The broken lines in the drawings depict portions of the ecology tab that form no part of the claimed design.

1 Claim, 7 Drawing Sheets
